[57] CLAIM

The ornamental design for a portable oxygen extender station, as shown and described.

DESCRIPTION

FIG. 1 is a perspective view of the oxygen extender station embodying my new design;

FIG. 2 is a top plan view of the same;

FIG. 3 is a rear elevational view of the same;
FIG. 4 is an elevational view from the left as viewed in FIG. 3; and

FIG. 5 is a front elevational view of the same.

The broken lines are shown for illustrative purposes only.

FIG. 2FIG. 1FIG. 3
